UNITED STATES PATENT OFFICE.

DAVID PELTON MOORE, OF WASHINGTON, DISTRICT OF COLUMBIA.

BASKET AND HAMPER.

No. 904,142.

Specification of Letters Patent.

Patented Nov. 17, 1908.

Application filed April 16, 1908. Serial No. 427,394.

To all whom it may concern:

Be it known that I, DAVID PELTON MOORE, a citizen of the United States, residing at Washington, in the District of Columbia, have invented certain new and useful Improvements in Baskets and Hampers, of which the following is a specification, reference being had therein to the accompanying drawing.

10 My present invention relates to improvements in baskets and hampers, the main object of my invention, being the provision of a novel form of canvas or like material basket or hamper, having a knock-down supporting frame; whereby economy in manufacture and storage, as well in transportation, is effected. In baskets of this character now upon the market, they are made so that they must always remain intact, thus occupying too great storage space, and when it comes to shipping from maker to user, the transportation charges are too great, as they are charged for space occupied, and not weight, as will be the case with my basket

25 or hamper.

In order to accomplish the objects of my invention, the canvas portion is made of two pieces; one piece forming the bottom being a plain rectangle, while the sides and ends 30 are made of the other piece, which is of peculiar and novel form, so as to provide reinforcements at the four corners, where the most wear is occasioned. These two strips of canvas, after the corners have been 35 formed upon the blank for the sides and ends, are sewed together to form in reality, a canvas bag, the upper edge of the bag, being securely fastened to the mouth extending and supporting rim of the frame. At the 40 corners, and where necessary at the sides, I provide threaded sockets, which when the bag is secured to the rim, are in line with the pockets formed at the corners and where desired in the sides of the blank, so that the 45 vertical supporting rods of the frame, may be inserted through the pockets and secured to the threaded sockets; the other ends of the vertical supporting rods being detachably secured to the runner of the basket or 50 hamper. By this construction the rims carrying the bags may be nested in dozens or half-dozens, the runners crated in similar numbers; and the vertical rods in bundles of six, with twelve or six bundles to a package. 55 Thus one dozen or one half dozen of my baskets or hampers will occupy when knocked

down, a space about equal to three of the baskets, that are now upon the market. The frame being constructed as I have done, will be just as strong, if not stronger, and altogether, a more durable, practical and economical basket or hamper than has heretofore been produced.

To clearly illustrate my hamper or basket, attention is invited to the accompanying drawings, in which:—

Figure 1 is a perspective view of a complete basket. Fig. 2 is a similar view of the frame work, with the canvas removed. Fig. 3 is a plan view of the blank for the sides and ends of the canvas. Fig. 4 is a similar view after being sewed, but before the blank is made continuous, and secured to the bottom. Fig. 5 is a plan view of the bottom's blank. Figs. 6 and 7 are detail views of the runner, illustrating their connections with the vertical supporting rods. Figs. 8 and 9 are detail views of the corner connections of the upper rim. Figs. 10, 11 and 12 illustrate the nesting feature.

Referring to the drawings:—The numeral 1 designates the runners, which may be in any number and run longitudinally of the basket or hamper, these runners being connected together by means of the transverse 85 slats or auxiliary bottom 2, which are secured in place against twisting by means of the metal plates 3. Detachably secured to these runners at predetermined points are the vertical corner supporting rods or pipes 4, and the intermediate or side vertical supporting rods or pipes 5, the upper ends of the corner rods or pipes being detachably connected to the lower connections 6, of the supporting rim 7, which is provided with the 90 intermediate rod connections 8. This much constitutes the knock-down supporting frame for the canvas bag or basket 9, which as illustrated in Figs. 3, 4 and 5 is made of the two strips of canvas 10 and 11, respectively, the 100 strip 10, constituting the sides 12 and the ends 13 of the bag or basket; and the reinforced vertical corner rod or pipe incasing pockets 14, a separate strip 15 forming the pockets for the intermediate rods or pipes 5. 105

In constructing my bag or basket, I form the blank for the sides and ends, as shown in Fig. 3, providing the same with the upper cut-away portions 16 and the oppositely arranged cut-away portions 17, the blank being folded first upon the dotted line 18, and then simultaneously upon the two dotted lines 19,

the same being stitched as indicated in dot-and-dash lines 20, Fig. 4. When this has been performed, the next step is to secure the edge 21 to the edge 22, on dot-and-dash line 23, thus making a continuous wall of the blank with the corner pockets formed, the strips 15 having been secured in place just previous to the securing of the ends. The lower edge 24 of the blank is now turned in and under and below the edges of the bottom blank 25, Fig. 5, and two rows of stitchings are made upon the dot-and-dash lines 26 of the two blanks, thus forming the bag or basket. The upper edge 26' of the blank as shown in Fig. 4, is folded outwardly upon the dotted line 27, and this edge is sewed to the supporting rim 7, the slit portions 28 allowing for a neat joint or lap around the corners of this rim. The stitching to the rim extends from one of the corner connections to the intermediate connection, and the fold is long enough to extend over the upper edges of the corner pockets 14 and intermediate pockets formed by the strips 15, thus closing these pockets at the top, but allowing them to be open upon the exterior of the bag at the bottom, so that the vertical rods or pipes will extend exteriorly, as shown in Fig. 1.

30 In Figs. 8 and 9, I have illustrated one method of securing the corners of the rim 7, rigidly together, a jam sleeve 29, being employed, but I would have it understood, that I can braze the corners and the intermediate 35 rod connections to the rim without departing from the spirit of my invention; or it may be that the entire rim will be made integral with any form of connecting means for the vertical rods. In securing the vertical rods 40 to the runners, I provide, preferably the threads 30 upon the lower ends of the rods, a shouldered nut 31 being rigidly secured as at 32, so that the lower end of the rods can be passed through the reduced opening 33, of the runner, so that the nut 31 will rest in the shouldered socket 34, and when the washer and nut 35 are tightly secured in place, as in Fig. 9, the rods will be held against turning, and thus properly support the rim and bag 50 or basket upon the runners, the bottom of the bag or basket resting lightly upon the transverse slats or auxiliary bottom 2, whose edges are rounded as at a, to prevent the bottom of the canvas from being cut through.

55 From the foregoing description taken in connection with the drawings, it will be seen that a dozen or half-dozen bags and their supporting rims may be nested, as shown in Fig. 10, their handles b, being tied together 60 to hold the same nested. The runners and auxiliary bottoms are crated as shown in Fig. 11, being held together either by strips c, nailed to the runners or a crate, as may be desired, while the vertical rods are tied in bundles of six or more, and these bundles

made in a package of six or a dozen, as may be desired, as shown in Fig. 12.

What I claim, as new, is:—

1. A knock-down frame for baskets, comprising longitudinal runners, an auxiliary bottom carried thereby, a rim, a series of supports for the rim detachably secured to the runners and rim, and means, bodily detachable, seated within and protected by the runners, for locking said supports to prevent them from turning in the runners and rim. 75

2. In combination with a knock-down frame, comprising longitudinal runners, a rim, a series of supports for the rim detachably secured to the runners and rim, and means, bodily detachable, seated within and protected by the runners, for locking said supports to prevent them from turning in the runners and rim, of a flexible receptacle 85 carried by said rim and depending within the supports.

3. In combination with a knock-down frame, of a flexible receptacle made of two strips of material, one strip forming the bottom and the other forming the sides and ends and also the covering for the supporting frame, the covering at the corners of the frame being doubled upon and around the frame and sewed in two parallel places one 95 upon each side of the frame to form reinforced corner protectors.

4. In combination with the runners, an auxiliary bottom carried thereby, a rim, a flexible receptacle carried by said rim and 100 provided with reinforced corner pockets which have a series of thicknesses on the exterior, detachable vertical supports entering said pockets from below and engaging the rim, and means for detachably securing said 105 supports in the runners and locking said supports against turning in the rim and runners.

5. In combination with the runners, an auxiliary bottom carried thereby, a rim, a receptacle made of flexible material and carried bodily by the rim, said receptacle being formed of two strips, one forming the bottom and the other the supporting edge, side and end walls of the receptacle, said last mentioned strip also having formed from the 115 body thereof vertical pockets, and a series of detachable vertical supports adapted to be incased in said pockets and supportingly fastened to the rim and runners.

6. A single blank forming the side and 120 end walls of a flexible rectangular receptacle, said blank being folded at intervals upon itself and secured to provide integral reinforced pockets, the reinforcement being formed of a series of integral layers of the 125 material of the blank.

7. A single blank forming the side and end walls of a flexible receptacle, and having a series of oppositely arranged cut-away portions upon its upper and lower edges, the 130

blank at said cut-away portions being folded and secured to provide integral reinforced pockets, as set forth.

8. A flexible receptacle, made from two strips of fabric, one strip forming the bottom, and the other secured thereto upon its lower edge and provided with an out-turned supporting upper edge and a series of reinforced pockets formed from the body of the strip by being folded vertically and secured to the strip by two lines of fastenings, whereby the pocket is formed between said lines of fastenings.

9. A basket or hamper, comprising runners, transverse slats connecting said runners and forming an auxiliary bottom, a rim, a flexible receptacle made of two strips of fabric, one forming the bottom, which rests upon the auxiliary bottom, and the other strip forming the side and end walls, and provided with exterior vertical corner pockets, the upper edge being secured to and incasing said rim, and a series of vertical supporting

rods incased in said pockets and detachably and securely fastened to the rim and runners. 25

10. A basket or hamper, comprising runners, transverse slats forming an auxiliary bottom, a rim, detachable vertical supports connected to the rim and runners, means mounted in the runners for locking the supports and preventing them from turning, and a flexible receptacle having its upper edge secured to the rim and resting within the vertical supports with its bottom upon the auxiliary bottom, and a series of pockets upon 30 the exterior of the receptacle open at the bottom to incase the upper ends of the vertical supports, which project below the open end 35 exteriorly of the receptacle.

In testimony whereof I affix my signature 40
in presence of two witnesses.

DAVID PELTON MOORE.
